Inventor

UNITED STATES PATENT OFFICE.

CHESTER W. BRINK, OF WILMINGTON, DELAWARE, ASSIGNOR OF ONE-HALF TO ELEAZER AINSWORTH, OF SAME PLACE.

GAFF-CLAMP.

SPECIFICATION forming part of Letters Patent No. 349,834, dated September 28, 1886.

Application filed May 24, 1886. Serial No. 203,131. (No model.)

To all whom it may concern:

Be it known that I, CHESTER W. BRINK, a citizen of the United States, residing at Wilmington, in the county of New Castle and State of Delaware, have invented certain new and useful Improvements in Gaff-Clamps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 In the usual method of rigging ships, schooners, &c., the gaff is supported entirely by the halyards, the gaff itself having an open jaw, which rests against the mast, and a loosely-fitting band, which is attached to the two ends 20 of the jaw, passing around the mast. The object of this band is to hold the gaff to the mast, and it is ordinarily loose, so as to enable the sail to be readily hoisted and lowered. The gaff being entirely supported by 25 the halyards, in case they break, as they frequently do in storms or squalls, the sail drops, and owing to this many vessels are lost.

The object of this invention is to provide such an attachment between the gaff and mast 30 as will not interfere with the hoisting and lowering of the sail, but which will enable the gaff to be quickly and easily clamped to the mast, so that in case the halyards break the gaff will be, nevertheless, supported in proper 35 position.

To this end the invention consists in a flexible clamping-band carried by the gaff-jaw, which can be quickly loosened and tightened from the deck. This connection can also be 40 used between the boom and mast, instead of the fixed screw-clamps which have hitherto been used.

The invention is illustrated in the accompanying drawings, in which Figure 1 is a 45 view of a boat provided with the improvement. Fig. 2 is a detached plan view of the clamp applied to the end of the gaff. Fig. 3 is a side view of the same, and Fig. 4 is a detail section in a plane indicated by the line 50 4 4.

A is the mast of the boat, B the boom, C the gaff, and D the sail.

E is the gaff-jaw, which consists of two horizontal connecting-arms, *a a*, and two laterally-projecting arms, *b b*, which are suitably carved 55 to fit the mast. The gaff may be either rigidly secured to the jaw or connected thereto by any desired means. Preferably it is secured thereto by a universal joint, which will permit the gaff to be turned in any direction 60 independently of the jaw, such a joint being shown in the drawings.

F is the clamping-band, which consists of a flexible metallic band which is supported upon the exterior of the arms *b b* of the jaw and 65 encircles the mast. The two ends of this band are secured to a tightening-lever, G, which is pivoted on a bolt, *c*, located between the arms *a a* of the jaw. The two ends of this band are secured to pins *d d*, carried by the tightening-lever on each side of the pivot-bolt. The band is held in position on the jaw by 70 means of raised overlapping edges *e e* on the jaw, and by the arms *a a*. When the tightening-lever is in the position shown in Fig. 2, 75 the band will be loose and the sail may be raised and lowered; but when the handle *g* of the lever is moved toward the mast (in the direction of arrow *h*) the band will be tightened and will clamp the jaw firmly to the 80 mast, thus supporting the gaff independently of the halyards. This clamping may be done in a moment's time, and by the use of suitable tackling may be easily accomplished from the deck of the vessel. To indicate how this 85 may be done, two eyes, *i* and *k*, are shown, carried by the jaw on opposite sides of the lever, and an eye, *l*, is shown on the end of the lever. A rope or cord, *m*, secured to the eye of the lever passes in opposite directions 90 through the eyes *i* and *k* to the deck. A pull on one end of this rope will clamp the band, and a movement in the opposite direction will loosen the same. The ropes may be secured in either position at the deck.

This clamping device not only serves to hold the gaff in any position desired and to be instantaneously operated, but it also prevents the sail from running in a blow, and may be also utilized in hoisting the sail. 95 100

I claim as my invention—

1. A clamping device for securing the gaff or boom of a vessel to the mast, consisting of a flexible tightening-band carried by the gaff or boom and encircling the mast, said band being arranged to be tightened and loosened, in combination with mechanism for tightening and loosening said band, substantially as set forth.
- 10 2. The gaff and a tightening-lever pivotally connected thereto, in combination with a tightening-band which encircles the mast and is secured at opposite ends to said lever, substantially as set forth.

3. A gaff-jaw and a tightening-lever pivoted thereto, in combination with a flexible tightening-band which encircles the mast and is attached at opposite ends to said lever on either side of the pivotal point thereof, substantially as set forth.

In testimony whereof I affix my signature in presence of two witnesses.

CHESTER W. BRINK.
